TOILET FLUSH VALVE
John R. Wolfgram, 558 E. Idaho Ave.,
St. Paul, Minn. 55101
Filed Oct. 24, 1965, Ser. No. 504,422
10 Claims. (Cl. 4—42)

This invention relates to an improvement in toilet flush valve and deals particularly with a siphon type valve capable of eliminating the ball type valve usually used in the flush tank discharge, and also eliminating the difficulties often experienced with such a form of valve.

Toilet flush valves have been by far the major difficulty experienced with modern type flush toilets. The valves of the type in question must remain open until the major portion of the water in the tank has been drained away, and must then seal the tank outlet so that leakage does not occur. As soon as this valve ceases to function properly, the water slowly drains into the toilet bowl, often resulting in a condition wherein the water is constantly flowing into, and out of, the flush tank. This not only creates a serious water leakage, but also often creates an annoying sound.

Siphon type flush valves have been used from time to time in an effort to obviate the difficulty with the ball type valve. Siphon valves, however, have usually been in the form of elongated tubes either of U-shaped form or of angular form having an end which terminates near the bottom of the flush tank, and an intermediate portion which extends above the normal water line in the flush tank. The main objections to devices of this type have been that they are considerably more expensive than the usual ball type valve, and they are normally much slower in operation due to the fact that all of the water in the tank must flow through the siphon tube on its way to the discharge. As a result of their relatively high cost and slow operation, they have not, to my knowledge, ever been sold in any great volume.

It is an object of the present invention to provide a flush valve of the siphon type which will empty the flush tank as quickly as any other type of valve of which I am familiar, and which is virtually fool-proof in its operation. The device comprises primarily of a flexible tube which is connected to the tank discharge and which is of substantially the same diameter as the discharge. To this flexible tube is connected a siphon head having an outlet end connected to the flexible tube, an inlet end through which the water may flow, and an intermediate bend which is normally above the level of at least a portion of the inlet and outlet ends of the siphon head. The present structure differs from previous structures in that the inlet head has a portion of its inlet end above the normal water level in the flush tank when the water therein is at its normal level. Rather than to have the end of the flush valve extend normally to a point adjacent the bottom of the flush tank, the suction head is short and is raised with the raising of the water level by means of a float attached to the siphon head. As a result, the discharge pipe attached to the tank is normally open to atmosphere through the inlet end of the siphon head when the flush tank is full.

A further feature of the present invention resides in the provision of a device of the type described in which the suction head is supported for pivotal movement about a fixed pivot. This fixed pivot is usually below the normal water line of the flush tank. As the buoyant member is secured to the siphon head, the siphon head will move in an arcuate path from a position engaging the bottom of the flush tank, at which time the tank is emptied, to a position in which the interior of the siphon head is exposed to air above the water level. When the tank is flushed, as by a pivotal handle supporting an arm con-

2

nected by a flexible member to the pivotal siphon head support, the siphon head is manually emersed, causing the water within the tank to flow through the siphon head, flexible tube, and the tank discharge until the tank is virtually empty. At this point, air enters the siphon head and the siphoning of the tank stops. At this point, the float attached to the underside of the siphon head will elevate the siphon head with the level of the water in the tank until the siphon head is in its starting position.

An important feature of the present invention resides in the provision of a siphon type flush tank discharge valve which may be produced at a cost which places it competitive with the cost of many of the so-called ball type discharge valves on the market. The structure is firmly molded of plastic and includes a lower portion which threads into the tank discharge and to which the flexible tube is attached, the siphon head at the end of the tube and which may be a part thereof, and an arm which is pivotally supported by the first molded piece and which serves to control the movement of the siphon head. This latter described part is what may be termed a bell-crank lever engaged with the siphon head at one end and with the manual toilet flushing means at the other end. By raising the latter described end of the bell crank lever, the end thereof engaging the suction head forces the suction head below the surface of the water in the tank, and permitting the water to siphon from the flush tank.

A further feature of the present invention resides in the provision of a siphon head having an inlet end which is on a plane inclining in one direction from the horizontal when the siphon head is in raised position, and inclining in the opposite direction with respect to the horizontal when the siphon head is in lowered position. As a result of this arrangement, when the siphon head is elevated to its raised position when the tank is full, the upper portion of the inlet end of the siphon head is above the water level, allowing air to enter the siphon head, while the bent intermediate portion of the siphon head is also above the water level, preventing the water from flowing from the inlet end of the siphon head to the outlet end thereof. When the tank is empty, the portion of the inlet end of the siphon head which was above the liquid level when the tank was filled is pivoted down into engagement with the bottom of the tank, and the water continues to drain from the tank until the water level reaches the highest point of the siphon head inlet end, at which time air enters the siphon head and breaks the siphoning action.

These and other objects and novel features of the present invention will be more clearly and fully set forth in the following specification and claims:

FIGURE 1 is a vertical sectional view through a flush tank showing the siphon type flush valve in the position it assumes when the tank is full.

FIGURE 2 is a view similar to FIGURE 1 showing the position of the valve when the tank is empty.

FIGURE 3 is a top plan view of the flush tank.

FIGURE 4 is a perspective view of the siphon type valve.

FIGURE 5 is an end elevational view of the base portion of the siphon valve.

FIGURE 1 illustrates in general a flush tank 10 of the type used on a toilet and having an outlet opening 11 in its bottom surface. A water supply pipe 9 extends into the tank 10 and is provided with a valve element 12 designed to maintain a constant water level, indicated at 13, in the tank 10. Alternatively, the water supply pipe 12 may be connected to a valve controlled by a float within the tank which accomplishes the same result.

The present device includes, in general, four major parts. These parts include a base fitting 14 which is illus-

strated by itself in FIGURE 5 of the drawings. The structure also includes a flexible tube 15 which forms the intermediate portion of the device. The third part comprises the siphon head 16. The fourth major part comprises the actuating lever 17 which is pivotally connected to the base portion 14 of the device and which is attached to the suction head 16 so that pivotal movement of the lever arm 17 serves to fill the tube 15 by emersion of the suction head 16 and to cause the suction head to drain the water from the tank 10.

The base unit 14 includes an externally threaded sleeve 19 designed to screw into a suitable fitting 20 connected to the outlet pipe 21 leading to the toilet bowl. As indicated in FIGURE 5, a U-shaped bracket 22 also forms a part of the base member 14. The U-shaped bracket 22 includes a base plate 23 which is arranged on a plane normal to the axis of the threaded sleeve 19, and a pair of parallel arms 24 extending upwardly from opposite ends of the base plate 23. The parallel arms 24 are preferably generally triangular in shape, tapering toward the upper end, and are provided with opposed coaxial pivots 25 near their upper ends. The base portion 14 also includes an inclined upwardly and forwardly inclined tubular portion 27 communicating with the interior of the threaded sleeve 19 and mounted on the upper surface of the base plate 23.

The flexible tube 15 may be of any suitable type, but preferably comprises a fluted or corrugated section of tubing made of flexible resilient plastic. The plastic is of a type to prevent any deleterious effect from water or substances in water which might reduce the flexibility of the material involved.

The siphon head 16 comprises a hollow tubular hook-shaped portion which is generally rectangular in cross-section, but which may be provided with a cylindrical neck 29. The tubular portion 15 encircles the substantially cylindrical projection 27 on the base member 14, and encircles the cylindrical end 29 of the siphon head 16. The tube 15 is sealed to the members it embraces at both ends of the tube.

The outlet end 29 of the siphon head 16 terminates at an angle of somewhat greater than 90 degrees from the plane of the inlet end 30 of the siphon head. Intermediate the inlet 30 and outlet 29, the interior of the siphon head includes a bend as indicated at 31. The concave under side of the siphon head 16 is provided with a block 32 of foam plastic or similar material on the concave side of the siphon head between the inlet and the outlet. This foam plastic block 32 acts as a float to elevate the siphon head as the water level rises, as will be described.

The lever 17 includes an elongated arm 33 having an offset end 34 secured to the convex surface of the siphon head 16. The lever 17 comprises a bell crank lever and is provided with an intermediate widened portion 35 including a pair of right angularly extending parallel ears 36 which are apertured to accommodate the pivot pins 25. In actual practice, the base portion 14 as well as the lever arm 17 are formed of plastic which is sufficiently resilient to permit the bracket sides 24 to be spread apart to the extent necessary to engage the pivot pins 25 in the apertured parallel ears 36. Alternatively, the pivot pins 25 may be removable for assembly purposes.

The end of the lever 17 opposite that attached to the siphon head 16 comprises an arm 37 which is at generally right angular relation to the arm portion 33. The intermediate widened portion 39 of the arm 37 is provided with a generally rectangular aperture 40. A tube 41 extends through the base portion 14 as indicated in FIGURE 2 of the drawings, and extends to the bottom level of the externally threaded sleeve. The tube is shown as extending above the liquid level in the tank and is connected by a tubular conduit 38 (see FIGURE 3) to the valve element 12 connected to the water supply pipe 9 to receive a small proportion of the water supplied

thereto. This water flows into the toilet bowl as the water is flowing into the tank 10 to refill the bowl. The side of the tube 41 most remote from the siphon head is supported by an arm 43 having a stop shoulder 44 thereon. 5 When in elevated position of the siphon head 16, the arm engages this stop shoulder to limit upward movement. If the tank overfills, the siphon head and tube 15 act as an overflow pipe.

As is indicated in FIGURE 1 of the drawings, the front 10 surface 46 of the tank 10 supports a shank 47 extending therethrough having an operating handle 49 on its outer end externally of the tank, and an arm 50 on its inner end internally of the tank. A flexible member 51 such as a chain or the like, is adjustably connected to the arm 15 50 and is connected to the outer extremity 52 of the end 37 of the bell crank lever 17. By pivoting the handle 49 in a counterclockwise direction, the arm 50 is elevated, pivoting the bell crank lever 17 in a clockwise direction. This action submerges the siphon head 16, filling the tube 20 15 and starting the siphoning action.

It will be noted that the inlet end 30 of the siphon end 16 is inclined so that the upper extremity of this head is slightly above the liquid level 13 when the siphon head is in its elevated position. However, when the bell crank lever 17 is pivoted, swinging the siphon head 16 downwardly below the water level 13, the inlet end 30 is swung toward a horizontal position, and the buoyant block 32 is swung above the level of the inlet end 30. In other words, the buoyant block 32 is only in position to expose the 30 inlet end 30 to atmosphere above the liquid level when the tube is substantially in the upright position shown in FIGURE 1. As shown in FIGURE 2, when the suction head is in its completely lowered position, the buoyant block is actually above the minimum water level 53 in 35 the tank 10. As indicated in both of the extreme positions shown in FIGURES 1 and 2, the buoyant block 32 always maintains the bend 31 of the siphon end above the water level, and the water would never drain unless the siphon head was manually swung into submerged position. 40 As the water level lowers, the effectiveness of the buoyant block 32 continually decreases until in the lowermost position of the suction head, indicated in FIGURE 2, there is no buoyant effect on the siphon head, and there will not be until the water level is raised to the point where the buoyant block 32 is partially submerged.

45 Because of the dimensions of the suction head 16 and the tube 15, the water in the tank 10 will flow from the tank just as quickly as the outlet passage will permit. By providing a buoyant means of supporting the suction head which at all times supports the bend 31 of the siphon head above the level of the water unless it is manually forced beneath the surface, a quick acting and extremely inexpensive discharge valve is produced.

50 In accordance with the patent statutes, I have described the principles of construction and operation of my improvement in toilet flush valve, and while I have endeavored to set forth the best embodiment thereof, I desire to have it understood that changes may be made within the scope of the following claims without departing from the spirit of my invention.

60 I claim:

1. A flush tank siphoning apparatus in combination with a flush tank having an outlet opening at its lower end, and liquid supply means adaptable to refill the tank to a predetermined level, the apparatus including:
65 a flexible tube connected to said outlet opening,
a hook-shaped hollow siphon head on said flexible tube having an inlet end, an outlet end connected to said tube, and an intermediate bend always above the level of portions of said inlet and outlet ends,
70 means pivotally supporting said siphon head for movement from a position with the inlet end of the siphon head closely adjacent to the tank bottom to a position in which a portion of the siphon head projects above said predetermined liquid level,
